UNITED STATES PATENT OFFICE

2,206,717

REFRIGERATOR DOOR CONSTRUCTION

William Paul Dodge, Erie, Pa., assignor to General Electric Company, a corporation of New York

Application August 30, 1938, Serial No. 227,518

7 Claims. (Cl. 20—35)

My invention relates to a refrigerator construction and more particularly to door sealing means for refrigerator cabinets.

Objects and advantages of my invention will become apparent as the following description proceeds and the features of novelty which characterize my invention will be pointed out with particularity in the claims annexed to and forming a part of this specification.

For a better understanding of my invention reference may be had to the accompanying drawings in which Fig. 1 is a front view of a refrigerator cabinet embodying my invention, Fig. 2 is an enlarged view partly in section of a portion of my refrigerator and Fig. 3 is an exploded view of details illustrating my invention.

I have provided a refrigerator cabinet in which the walls and door comprise inner and outer metallic shells with insulating material therebetween. The space between the shells is closed by a breaker strip. In accordance with my invention, I have provided a gasket on the door or the wall of the refrigerator adjacent the door opening which has an apron concealing one edge 25 of the breaker strip so that rough-sawn breaker strips may be used and the grinding operation which is now required to improve the appearance of the strips may be eliminated. My invention also contemplates the formation of a channel 30 in the side of the gasket lying against the outer shell and a rib or plurality of projections or ears on the outer shell for engaging the channel in the gasket. This construction co-operates with the apron to reinforce the gasket so that a 35 lighter material may be used for the gasket and the number of screws required to support the breaker strips is reduced to four for each strip, that is, two on each side of the strip at the ends thereof.

I have shown a refrigerator 10 of the household type having a food compartment 11 closed by a door 12. As best shown in Fig. 2 the walls of the refrigerator cabinet include an inner shell 13 and an outer shell 14, the opening therebetween being closed by the breaker strip 15 held in position by means of retaining strips 16 of any suitable material such as rubber or metal, for example. The inner shell 13 is provided with an inwardly directed flange 17 while the outer shell 14 is provided with a flange 18 in substantial alignment with flange 17. Suitable heat-insulating material 19 is inserted in the space between the inner and outer shells.

In order to support rigidly the inner and outer shells of the cabinet in the desired space rela-

tionship, the shells are connected by a plurality of spacers 20 within the construction. These spacers are preferably of non-metallic, non-hygrosopic material to minimize heat loss between the shells. The retainer strips 16 are roughly S-shaped, comparatively rigid and extend the full length of the breaker strip. Therefore, lips 22 on the retainer strips 16 serve to hold the breaker strip against the shells and also to conceal the edges of the breaker strip 15. Screws 21 are provided at each end of breaker strips 15 to secure the retaining strips 16, the breaker strip 15 and spacers 20 in the proper relationship with the shells 13 and 14.

The construction of the door 12 is similar to that described above in most respects. I have provided an inner shell 23 and an outer shell 24 with suitable insulating material 25 therebetween. The inner shell 23 is provided with an inwardly directed flange 26 while the outer shell 23 is provided with a flange 27 having a lateral extension 27a in substantial alignment with flange 26. In forming the lateral extension 27a the outer shell is bent back upon itself to form a groove 28 around the edge of the door.

In order to retain the shells in the desired spaced relationship, a plurality of spacers 29 is employed of the same material used for the spacers 20. A breaker strip 30 serves to close the opening between the inner and outer shells. 30 Breaker strips 15 and 30 are formed preferably of non-metallic, non-hygrosopic material. Resinous products, such as those known under the trade names Bakelite, Textolite, etc., are well adapted to this purpose. The inner edge of 35 breaker strip 30 is supported in position against inner shell 23 by means of a retaining strip 16. The outer edge of the breaker strip 30, however, extends part way across the groove 28, thereby forming a recess for the retention of the anchor- 40 ing bead 32 of a door sealing gasket 33 of suitable material, such as rubber for example, having a striking bead 33a.

Gasket 33 is provided with an apron 34 which conceals the outer edge of the breaker strip 30. 45 I have provided a longitudinal channel 35 in the opposite side of the gasket 33. A plurality of ears or lances 36 is shown struck-out from the flange 27 of the outer shell 24 which are adapted to engage the channel 35, thereby co-operating 50 with the apron 34 to reinforce the gasket along the entire length of the breaker strip. By properly positioning the projections 36 the apron 34 will be pressed tightly against the breaker strip 30 throughout the length thereof. By thus pro- 55

viding a gasket having a portion thereof arranged to cover an edge of the breaker strip and means for engaging the gasket in the vicinity of the concealing portion or apron adjacent the breaker strip, such as a groove in the side 5 of the gasket opposite the apron and one or more suitable projections on the outer shell, I am enabled to use a relatively light gasket which conceals the edge of the breaker strip, thereby 10 improving the appearance of the assembly, and yet provide sufficient support for the breaker strip throughout its length to permit reduction of the number of screws required in the past to 15 secure the breaker strip in place between the inner and outer shells.

It will be obvious that instead of punching out the ears or projections 36 a plurality of separate 20 projections may be secured to the flange 27 in any suitable manner as by welding or, if desired, a rib extending around the door opening might be 25 provided for engagement with channel 35. It will also be obvious that if projections 36 are provided, a plurality of depressions might be provided in the gasket 33 instead of the channel 35 30 for the retention of the projections 36.

Screws 31 are provided at each end of each door breaker strip 30 for assembly purposes.

While I have shown and described my invention as applied to specific refrigerator construction, I do not desire my invention to be limited to the particular construction shown and described and I intend in the appended claims to cover all modifications within the spirit and scope of my invention.

35 What I claim as new and desire to secure by Letters Patent of the United States, is:

1. In a refrigerator cabinet including a door and walls of the type having inner and outer shells joined by a breaker strip, sealing means for 40 sealing the space between the door and the walls defining the door opening including a gasket having a portion thereof engaging a breaker strip, a channel in said gasket adjacent said breaker strip, and reinforcing means projecting from the 45 outer shell into said channel.

2. In a refrigerator cabinet including walls and a door of the type having inner and outer shells joined by a breaker strip, sealing means including a gasket having an apron on one side 50 thereof for engaging a breaker strip, a channel in the opposite side of said gasket and adjacent said breaker strip, and means projecting from the outer shell for engagement with said channel.

3. Sealing means for sealing the space between 55 the door and walls of a refrigerator cabinet of the type having inner and outer metallic shells with insulating material therebetween and a breaker strip of low heat conductivity closing the opening between said shells, including a gasket, an anchoring portion on said gasket adapted to be retained by said outer shell, an apron on one side

of said gasket engaging one edge of said breaker strip, a channel in the opposite side of said gasket and adjacent said breaker strip, a projection extending from said outer shell for engagement with said channel.

4. Sealing means for sealing the space between the door and walls of a refrigerator cabinet of the type having inner and outer metallic shells with insulating material therebetween and a breaker strip of low heat conductivity closing the 10 opening between said shells, including a gasket, an anchoring portion on said gasket, a groove in said outer shell adjacent the outer edge of said breaker strip, said breaker strip extending part way across said groove to form a recess for retaining said anchoring portion, an apron on one side of said gasket extending across a portion of said breaker strip, a channel in the opposite side of said gasket and a plurality of projections extending from said inturned portion of said outer 15 shell into engagement with said channel for pressing said apron against said breaker strip.

5. A refrigerator construction comprising inner and outer metallic shells, heat insulating material between said shells, a plurality of spacers of 20 low heat conductivity separating said shells, a breaker strip of thermally resistant material closing the opening between said shells, a retaining strip engaging one edge of said breaker strip, a groove in said outer shell adjacent the other edge 25 of said breaker strip, a door sealing gasket, said gasket having an anchoring bead adapted to be retained in said groove, an apron on said gasket extending over a portion of said breaker strip, said gasket also having a depression adjacent 30 said breaker strip in the side thereof which engages said outer shell, and a projection on said outer shell for engaging said depression.

6. Sealing means for sealing the space between the door and walls of a refrigerator cabinet of 40 the type having inner and outer metallic shells with heat insulating material therebetween and a breaker strip of low heat conductivity closing the opening between said shells, including a gasket having a striking bead, a portion of said gasket being arranged to conceal an edge of said 45 breaker strip, and means engaging said gasket in the vicinity of said portion for reinforcing said gasket.

7. Sealing means for sealing the space between 50 the door and walls of a refrigerator cabinet of the type having inner and outer metallic shells with heat insulating material therebetween and a breaker strip of low heat conductivity closing the opening between said shells, including a gasket having a striking bead, an apron extending from one side of said gasket for concealing an 55 edge of said breaker strip and means on the other side of said gasket for reinforcing said gasket in the vicinity of said apron.

W. PAUL DODGE.
